CLAIM

The ornamental design for a stand accessory for a test and measurement instrument, as shown and described.

DESCRIPTION

FIG. 1 is a top, rear, left, isometric view of a stand accessory for a test and measurement instrument showing the new design in conjunction with an environment in a first operating position;

FIG. 2 is a top, front, right isometric view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof;

FIG. 9 is a top, rear, left, isometric view of a stand accessory for a test and measurement instrument showing the new design in conjunction with an environment in a second operating position;

FIG. 10 is a left side elevational view thereof; and,

FIG. 11 is a right side elevational view thereof.

The broken lines in the drawings depict environmental structure as well as unclaimed portions of the stand acces-
